PARKER C. THOMPSON, OF WRIGHT CITY, MISSOURI.

COMBINATION LOCK MECHANISM FOR VALVES.

1,202,124.

Specification of Letters Patent. Patented Oct. 24, 1916.

Application filed October 16, 1914. Serial No. 866,920.

To all whom it may concern:

Be it known that I, PARKER C. THOMPSON, a citizen of the United States, and resident of Wright City, county of Warren, State of Missouri, have invented certain new and useful Improvements in Combination Lock Mechanism for Valves, of which the following is a specification.

This invention relates to improvements in 10 a combination lock mechanism for valves, and has for its object a combination tumbler mechanism so located in a suitable housing and arranged to be brought in contact with a lever mechanism directly connected to a 15 valve for locking said valve in a cut-off position whenever it is desired to do so.

A further object of this invention is to construct a device which can be used for controlling the manipulation of the valve 20 wherever the valve may be applicable, such as on automobiles, water supply pipes for buildings, gas, or in fact any purpose where valves are used in connection with a pipe system; and where it is found necessary at 25 times to lock the valve and keep the same in a locked position, in order to prevent passage of the liquid or gas.

The essential object of my invention is to 30 construct a combination lock mechanism arranged conveniently on an automobile, the valve being arranged in the pipe connection anywhere between the fuel tank and the engine and to be able to close the valve and lock the same in order to prevent the flow 35 of the fuel, thereby preventing the automobile from being stolen when the said machine is left on the siding unguarded.

Figure 1, is a rear view of my invention with the plate of the casing removed, showing 40 the construction and relative position of the parts when locked. Fig. 2, is a front view of my invention showing the combination dial and the handle by which the valve mechanism is controlled. Fig. 3, is a 45 vertical sectional view of the same, taken approximately through the center of the combination locking mechanism. Fig. 4, is a view of one side of one of the tumbler disks made use of. Fig. 5, is a reversed 50 view of the same. Fig. 6, is a detail side view of the combined tumbler mechanism detached from the casing. Fig. 7, is an edge view of the same. Fig. 8, is a top plan view of the same. Fig. 9, is a detail perspective view of the dog made use of in connection with the tumbler mechanism. Fig.

10, is a detail perspective view of the valve operating arm. Fig. 11, is a detail perspective view of one of the connecting links made use of in completing the valve operating mechanism. Fig. 12, is a detail perspective view of the valve locking plunger. Fig. 13, is a detail central sectional view of the primary tumbler disk.

In the construction of my invention I 65 provide a suitable casing or housing 14, arranged into an upper compartment 15, for the housing of the tumbler mechanism and a lower compartment 16, for the housing of the valve and its opening mechanism. 70 These two compartments are divided by a wall 17, this wall being provided with an opening 18, through which the valve locking plunger 19, operates whenever the tumbler mechanism is removed from its position over 75 the opening or aperture 18. The valve operating mechanism consists in addition to the valve locking plunger 19, of a rocking arm 20, firmly secured to a shaft 21, which has bearing in a projection 22, formed on 80 the rear wall of the housing; the forward end of said shaft projecting through the front wall 23, of the housing and on the same is a handle 24, by which said shaft can be operated. The one end 25 of the rocking arm is pivotally attached to the valve locking plunger 19, and the opposite end 85 of said rocking arm is connected to links 26, each formed as shown in Fig. 11. The bifurcated ends 27, of the links, straddle the 90 valve operating arms 28, which are two in number and constructed as that shown in Fig. 10. The square opening 29 of the arms is firmly fitted over the valve stem 30, which controls the inner operating mechanism of 95 the valve 31, which valve may be of any ordinary construction by which the fluid passing through the connecting pipes 32, may be shut-off.

The combination locking mechanism which 100 is located in the compartment 15, consists of a casting 33, having a dependent arm 34, which is arranged to contact with the upper surface of the valve locking plunger, and said casting above the depending arm terminates into a wider and broader portion; the same having an internal recess or opening 35, in which are located a plurality of tumbler disks, preferably three in number and which will be designated as tumbler 105 disks 36, 37, and 38. The top of this casting is provided with an integral cross-bar 39,

from which projects a guide 40, under which the dog 41, is located and held from lateral movement during its operation. This dog 41, is pivotally connected to the casting at 5 the point indicated by the numeral 42, and said dog is also provided with a projecting bar 43, which extends the entire width of the casting, and is for the purpose to lodge within the recesses 44, formed on the tumbler disks, for holding and locking said tumblers in alinement whenever said tumbler disks are in position by which the entire mechanism can be released from its locking position over the top of the valve locking plunger 19. The front wall of the housing is provided with a sleeve 45, on which the casting is mounted and in this sleeve is inserted a spindle 46, which is formed integral with the knob 47, which operates the dial 48, for manipulating the combination. And to the rear end of the spindle 46, is firmly attached a primary tumbler disk 49. This disk is provided with a notch or recess 50, on its outside in which the tooth 51, of the dog is designed to be seated, and on the inner surface of the disk is a projecting pin 52; this pin operates in a groove 53, formed on one surface of the tumbler disk 38, the groove having a projection 54, against which the pin 52, contacts for rotating this particular tumbler disk. The opposite surface of this disk is also provided with a pin which rides in a groove 55, formed in the disk 37. The construction is identical with the groove 53, of the disk 38, and its opposite surface is provided with a pin which rides in a similar groove in the disk 36, whose construction is identical with those previously described.

On one wall of the housing is firmly located lugs or projections 56 and 57, and are in a position as shown in Figs. 1 and 9. These lugs are for the purpose to limit the upward movement of the bar 43, of the dog; and when the tumbler mechanism is shifted to one side as shown by dotted lines in Fig. 1, so that its dependent lug is away from the plunger.

The bar 43, is seated in all of the recesses 44, of the tumbler disks, and the end of the bar is located under the lug 56, thereby preventing the tumblers from becoming shifted while in this position.

When locking the valve or placing the same in a position as shown in Fig. 1, the knob of the combination is turned so that the mechanism is directly over the plunger, as shown by solid lines in Fig. 1. When in this position the bar 43, of the dog, is brought away from the under surface of the lug 56, and is permitted to rise slightly above the periphery of the tumbler disks, when operating the knob to the left in order to disengage or mix-up the tumbler disks, and by turning the knob to the left the dog

is raised out of its position with the primary tumbler disk by reason of the inclined surface of the tooth 51, contacting with the inclined surface of the notch or depression 50 in the disk. And when said tumblers are so disengaged it will be utterly impossible to open the valve unless one is familiar with the combination necessary for operating the combination mechanism.

On the front plate is located a latch 57, the spring bolt 58, thereof is arranged to seat itself into a notch 59, formed in the plunger 60, located on the shaft. The object of this is to prevent the valve mechanism from shifting when in open position and this is particularly designed as a safeguard when the device is used on automobiles, in order to prevent the mechanism from accidentally being placed out of its set position by the jolting of the running machine.

Having fully described my invention what I claim is:

1. A device of the character described comprising a casing having an upper compartment and a lower compartment; a spindle extending into the upper compartment; a plurality of tumbler disks located thereon, a locking casting located in the upper compartment; a locking dog located in the casing and arranged to contact with the tumbler disks; a valve; and a valve operating mechanism located in the lower compartment, a plunger connected to the valve operating mechanism and arranged to be held in locked position by the casting in the upper compartment, and means for operating the valve mechanism; and a locking mechanism for engaging or disengaging a connection between the two, substantially as specified.

2. A device of the class described comprising a casing having an upper compartment and a lower compartment; a valve located in the lower compartment; a lever mechanism located in the lower compartment and connected to the valve; a plunger connected to the valve operating mechanism and extending into the upper compartment; a tumbler mechanism located in the upper compartment adapted to be operated by a combination disk, and a casting connected to the tumbler mechanism for holding the plunger in depressed position substantially as specified.

3. A device of the class described comprising a casing divided into two compartments, a valve mounted in the lower compartment, a rocking lever mounted in the lower compartment, a plurality of links connecting one end of the rocking lever with the valve, a plunger connected with the opposite end on the rocking lever and extending into the upper compartment, a handle connected to the rocking lever and extending through the casing, a latch mounted on

the casing for holding the valve in open position, a combination operated mechanism mounted in the upper compartment, and a rocking casting for holding the plunger in 5 locked position substantially as specified.

4. A device of the class described comprising a casing divided into an upper and a lower compartment, a removable front closing both compartments, a spindle extending through the front into the upper compartment, a combination disk and knob on the spindle and outside the casing, a plurality of disks mounted on the spindle and within the upper compartment, a casting 10 having an elongated projection mounted on the spindle and incasing the disks, a tumbler mechanism hingedly connected to the casting, means for engaging the tumbler mechanism with the disks, means for partially rotating the casting, a valve mounted in the 15

lower compartment, a rocking lever mounted in the lower compartment, a shaft extending into the lower compartment on which the rocking lever is mounted, a handle mounted on said shaft and without the casing, a plurality of links connected to one end of the rocking lever and the valve, a plunger connected to the other end of the rocking lever and extending into the upper compartment, and a latch mounted on the 20 front for holding the valve in open position substantially as specified.

In testimony whereof, I have signed my name to this specification, in presence of two subscribing witnesses.

PARKER C. THOMPSON.
